(57) **CLAIM**

The ornamental design for an ear spoon, as shown and described.

DESCRIPTION

FIG. 1 is a bottom, front, left perspective view of an ear spoon, showing my new design;

FIG. 2 is a top, rear, right perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof; and,

FIG. 9 is an enlarged view of detail "9", identified in FIG. 1.

The broken lines are included for the purposes of illustrating portions of the ear spoon that form no part of the claimed design.

1 Claim, 9 Drawing Sheets
